UNITED STATES PATENT OFFICE.

AUGUSTUS KEMPKEY, OF SAN FRANCISCO, CALIFORNIA.

HIP REIN-SUPPORT.

SPECIFICATION forming part of Letters Patent No. 397,922, dated February 19, 1889.

Application filed December 3, 1888. Serial No. 292,554. (No model.)

To all whom it may concern:

Be it known that I, AUGUSTUS KEMPKEY, a citizen of the United States, residing at San Francisco, in the county of San Francisco 5 and State of California, have invented certain new and useful Improvements in Hip Rein-Supports, of which the following is a full, clear, and exact description, such as will enable others skilled in the art to which it appertains 10 to make and use the same.

The accompanying drawing is referred to and made a part of this specification.

The drawing shows a perspective view of my invention and the manner of attaching it 15 to the harness.

The object of my invention is to provide a support for the driving-reins attached to the harness at the junction of the hip and back straps, keeping them upon the horse's back 20 and above his tail, preventing the reins getting under the horse's tail in "fly time" or at any time, and from getting caught in the harness. It may be of metal or any other suitable material, and plated and ornamented to 25 match the other trimmings of the harness.

I do not confine my invention to the exact shape of the support shown in the drawing; but it may be constructed of a form and shape to suit the taste and convenience of the user.

It consists of a bar, A, which has two loops, 30 B B, formed on its under side for the passage of the hip-strap through them, space for the back-strap being left between said loops. This bar is bent upward in the middle at a', and it is also bent over upon itself at each end 35 to form open spaces A' for the reception of the reins. The ends of the said bar are bent upward, leaving a space, a, between them, through which the reins may be passed to said open spaces A'. It is easily attached to and 40 removed from the harness.

Having thus described my invention, what I claim as new, and desire to secure by Letters Patent, is—

A rein-support consisting of a bar bent up- 45 ward at its middle portion and at each end bent upon itself to form open spaces for the reception of the reins, the end bent upward, leaving a space between said ends through which the reins may be passed to said open 50 spaces, the under side of said bar being also provided with loops, for the purpose set forth.

AUGUSTUS KEMPKEY.
